UNITED STATES PATENT OFFICE.

JOSEPH SILVANO FELIZ, OF CONCEPCION, CALIFORNIA.

OIL-WELL PUMP.

Application filed April 4, 1921, Serial No. 458,216. Renewed April 27, 1923.

To all whom it may concern:

Be it known that I, JOSEPH S. FELIZ, a citizen of the United States, residing at Concepcion, in the county of Santa Barbara and State of California, have invented certain new and useful Improvements in Oil-Well Pumps, of which the following is a specification.

This invention relates to oil well pumping apparatus and has as one of its primary objects to provide an apparatus which will be especially adapted for pumping oil from wells which have a tendency to "sand up" or which produce very thick oil.

Another object of the invention is to provide a pumping apparatus which will be highly efficient in its operation and which will elevate the oil in a steady and positive manner and with the application of the minimum power.

Another object of the invention is to provide an oil pumping apparatus so constructed that the same will not be liable to become clogged even where a comparatively thick oil is delivered by the well.

Another object of the invention is to provide a novel construction and arrangement of stand valves.

In the accompanying drawings:

Figure 1 is a perspective view of an apparatus embodying the invention;

Figure 2 is a detail vertical longitudinal sectional view through the lower end of the well tubing and the associated parts of the pumping apparatus;

Figure 3 is a horizontal sectional view on the line 3—3 of Figure 2 looking in a downward direction;

Figure 4 is a similar view on the line 4—4 of Figure 2 looking in a downward direction;

Figure 5 is a similar view on the line 5—5 of Figure 2;

Figure 6 is a perspective view of one of the standing valves and the associated parts;

Figure 7 is a detail vertical sectional view through a part of the apparatus.

In the drawings, the numeral 1 indicates a Samson post upon which is mounted the usual walking beam indicated by the numeral 2. A shaft 3 is mounted in juxtaposition to the Samson post 1 and carries a pulley 4 to which power is applied by a belt 5 driven from any suitable prime mover.

A pitman 6 connects one end of the walking beam 2 with a crank pin 7 upon the pulley 4 and provides for the transmission of power from the shaft 3 to the walking beam 2. The usual temper screw 8 is connected with the other end of the walking beam 2 and has the usual swivel 19 connected in the usual manner with the sucker rod 10 operating in the well tubing which is indicated by the numeral 12. The structure above described is that ordinarily found in oil well pumping apparatus of this class but in carrying out the present invention, the rod 10 is to be given rotative motion as well as the usual reciprocatory motion, the lower portion 11 of the sucker rod 10 being equipped at suitable intervals in its length with spiral or screw blades which through reciprocation and rotation operate to elevate by suction the oil entering the well tubing past the stand valves, as will presently be explained. In order that rotary motion may be imparted continuously to the rod 10 a system of gearing is provided between the said rod and the shafts 3 and 10.

Another object of the invention is to provide a novel construction and arrangement of stand valves.

In the accompanying drawings:

Figure 1 is a perspective view of an apparatus embodying the invention;

Figure 2 is a detail vertical longitudinal sectional view through the lower end of the well tubing and the associated parts of the pumping apparatus;

Figure 3 is a horizontal sectional view on the line 3—3 of Figure 2 looking in a downward direction;

Figure 4 is a similar view on the line 4—4 of Figure 2 looking in a downward direction;

Figure 5 is a similar view on the line 5—5 of Figure 2;

Figure 6 is a perspective view of one of the standing valves and the associated parts;

Figure 7 is a detail vertical sectional view through a part of the apparatus.

In the drawings, the numeral 1 indicates a Samson post upon which is mounted the usual walking beam indicated by the numeral 2. A shaft 3 is mounted in juxtaposition to the Samson post 1 and carries a pulley 4 to which power is applied by a belt 5 driven from any suitable prime mover.

A pitman 6 connects one end of the walking beam 2 with a crank pin 7 upon the pulley 4 and provides for the transmission of power from the shaft 3 to the walking beam 2. The usual temper screw 8 is connected with the other end of the walking beam 2 and has the usual swivel 19 connected in the usual manner with the sucker rod 10 operating in the well tubing which is indicated by the numeral 12. The structure above described is that ordinarily found in oil well pumping apparatus of this class but in carrying out the present invention, the rod 10 is to be given rotative motion as well as the usual reciprocatory motion, the lower portion 11 of the sucker rod 10 being equipped at suitable intervals in its length with spiral or screw blades which through reciprocation and rotation operate to elevate by suction the oil entering the well tubing past the stand valves, as will presently be explained. In order that rotary motion may be imparted continuously to the rod 10 a system of gearing is provided between the said rod and the shafts 3 and 10.

Another object of the invention is to provide a novel construction and arrangement of stand valves.

In the accompanying drawings:

Figure 1 is a perspective view of an apparatus embodying the invention;

Figure 2 is a detail vertical longitudinal sectional view through the lower end of the well tubing and the associated parts of the pumping apparatus;

Figure 3 is a horizontal sectional view on the line 3—3 of Figure 2 looking in a downward direction;

Figure 4 is a similar view on the line 4—4 of Figure 2 looking in a downward direction;

Figure 5 is a similar view on the line 5—5 of Figure 2;

Figure 6 is a perspective view of one of the standing valves and the associated parts;

Figure 7 is a detail vertical sectional view through a part of the apparatus.

In the drawings, the numeral 1 indicates a Samson post upon which is mounted the usual walking beam indicated by the numeral 2. A shaft 3 is mounted in juxtaposition to the Samson post 1 and carries a pulley 4 to which power is applied by a belt 5 driven from any suitable prime mover.

The sucker rod 10 is formed in sections as usual and the sections may be of any 110

2
required number and length and the lowermost one of these sections is indicated in the drawings by the numeral 33 and is formed with an axially extending bore 34 and provided with a flared lower end 35, the bore being designed to receive a guiding rod or stem 36 as illustrated in Figure 2 of the drawings and the flared end 35 providing means whereby the end of the said 10 guiding rod or stem may be guided with certainty into the bore 34 when the sucker rod is lowered into the well tubing. The said guiding rod or stem will presently be more specifically described.

15 At suitable intervals in its length, for example every one hundred feet or so, the sucker rod is provided with Archimedean screws indicated in general by the numeral 37 and each comprising a spiral blade 38 20 extending about and secured to the respective sections of the sucker rod 11 and provided with a peripheral upstanding flange 39 closely fitting the wall of the well tubing 12. In order to provide a fluid-tight fit between each of the Archimedean screws and the well tubing, each of the screws is provided throughout a suitable portion of the 25 length of its lower part with a packing 40 of asbestos applied and secured to the outer surface of the upstanding flange 39. It will now be evident that upon reciprocation of the sucker rod, the several screws will act as pistons to create a suction in the well tubing, and, simultaneously the rotation of 30 the sucker rod during its reciprocatory motion will result in the sections acting upon the column of oil in the well tubing to elevate the same. Thus the apparatus is designed to act in a highly effective manner 35 in elevating the oil within the well tubing even though there be a tendency for the well to "sand up" or the oil produced be relatively thick.

40 The oil drawn into the well tubing 45 through the lower end thereof is trapped by an arrangement of stand valves which will now be described. The numeral 41 indicates a cap which is provided with a threaded flange 42 adapting the cap to be fitted onto 50 the end of the well tubing and thus close the said tubing. This cap constitutes a support for the cages of the stand valves and each of said valves is indicated in general by the numeral 43 and comprises a cage consisting 55 of lower and upper heads 44 and 45 connected in spaced relation by bars 46. The head 44 is provided with a reduced externally threaded extension 47 projecting from its lower end and fitted through an opening 60 48 formed in the cap 41, a nut 49 being threaded onto the extension and bearing against the under side of the cap, the lower end of the head 44 resting upon the upper side of the cap. In this manner the cage is 65 secured in upright position upon the cap,

and the head 44 of the cage is formed with a passage 50 extending axially therethrough and terminating at its upper end in a valve seat 51 upon which normally rests a ball valve 52 confined by the bars 46 of the cage, 70 the valve being adapted to lift from its seat upon inrush of oil into the well tubing and to close in the event there is any momentary or prolonged cessation of the suction force created by the reciprocation of the Archimedean screws. The head 45 of each cage is likewise provided with a reduced threaded extension indicated by the numeral 53 and this extension is fitted through an opening 54 formed in a circular plate 55, this plate resting upon the upper end of the head 45, and a nut 56 being threaded onto the extension and bearing upon the upper side of the plate. The plate 55 fits snugly within the well tubing and serves to maintain the 80 upper ends of the valve cages suitably spaced and properly relatively positioned. A passage 57 is formed axially in the head 55 so that the oil which has entered through the passage 50 in the head 44 may pass into 85 the lower portion of the well tubing 12 where it is trapped.

90 The guide rod or stem 36 hereinbefore referred to is provided with a reduced threaded lower end 58 fitted through an opening 59 formed centrally in the cap 41, and a nut 60 is threaded on to this end of the rod and serves to anchor the same to the cap, the rod 95 extending perpendicularly from the cap and concentric to the series of stand valves and through an opening 61 formed centrally in the plate 55, the upper portion of the rod projecting into the bore 34 of the sucker rod section 33 so as to guide the section in its movement and thus guide the lower end of the sucker rod as a whole.

100 In order that oil may pass freely into the well tubing past the plate 55, the said plate is preferably formed as for example at 105 points between the openings 54 which receive the upper ends of the valve cages, with openings 62.

Having thus described the invention, what is claimed as new is:

1. In pumping apparatus, a tubing, a 110 helical piston operating therein, and means operating to reciprocate and rotate said piston.

2. In pumping apparatus, a tubing, a helical piston operating therein, and means 115 operating to simultaneously reciprocate and rotate said piston.

3. In pumping apparatus, a tubing, a pump rod extending into the tubing, a helical piston carried by the said rod and fitting the tubing, and means operable to 120 simultaneously reciprocate and rotate the said rod.

4. In pumping apparatus, a tubing, a pump rod operating in the tubing, helical

pistons carried by the rod, means for reciprocating the rod, a gear through which the rod is slidably fitted, and means for rotating the gear during reciprocation of the rod.

5. In pumping apparatus, the combination with a tubing, a pump rod extending into the tubing, a walking beam for recipro-

cating the rod, and means for operating the walking beam, of means operated by the beam operating means for rotating the rod, ¹⁰ and a helical piston carried by the rod.

In testimony whereof I affix my signature.

JOSEPH SILVANO FELIZ. [L. s.]
